US00D615110S

(12) **United States Design Patent**
Flory et al.

(10) **Patent No.:** US D615,110 S
(45) **Date of Patent:** ** May 4, 2010

(54) **SORTING DEVICE**

(75) Inventors: **Markus Flory**, Niederkassel (DE);
Rainer Forster, Niederkassel (DE);
Christian Weinsheimer, Gummersbach (DE)

(73) Assignee: **mk Sorting Systems GmbH**, Troisdorf (DE)

(**) Term: **14 Years**

(21) Appl. No.: **29/292,374**

(22) Filed: **Oct. 10, 2007**

(51) **LOC (9) Cl.** 15-99

(52) **U.S. Cl.** D15/145

(58) **Field of Classification Search** D15/122, D15/147, 199; 209/542, 543, 573; 221/266

See application file for complete search history.

(57) **CLAIM**

The ornamental design for a sorting device, as shown.

DESCRIPTION

FIG. 1 is a perspective view of a sorting apparatus or terminal; FIG. 2 is a front view of the sorting apparatus or terminal, as shown in FIG. 1;

FIG. 3 is a rear view of the sorting apparatus or terminal, as shown in FIG. 1;

FIG. 4 is a side view of the sorting apparatus or terminal, as shown in FIG. 1;

FIG. 5 is a side view, opposite the side view shown in FIG. 4, of the sorting apparatus or terminal, as shown in FIG. 1;

FIG. 6 is top view of the sorting apparatus or terminal, as shown in FIG. 1; and,

FIG. 7 is bottom view of the sorting apparatus or terminal, as shown in FIG. 1.
